CLAIM

The ornamental design for a bookcase as shown and described.

DESCRIPTION

FIG. 1 is a perspective view of the bookcase;
FIG. 2 is a front elevational view of the bookcase;
FIG. 3 is a rear elevational view of the bookcase;
FIG. 4 is a right side elevational view of the bookcase;
FIG. 5 is a left side elevational view of the bookcase;
FIG. 6 is a top plan view of the bookcase; and,
FIG. 7 is a bottom plan view of the bookcase.

The broken line portions of the drawings are included to show portions of the article that form no part of the claimed design and represent environmental structure only.

1 Claim, 6 Drawing Sheets
